CLAIM

The ornamental design for a speaker's stand, as shown and described.

DESCRIPTION

FIG. 1 is a front elevational view of a speaker's stand showing my design;

FIG. 2 is a side elevational view taken from the right in FIG. 1;

FIG. 3 is a top elevational view; and

FIG. 4 is a rear elevational view.

The side of the stand not shown is a mirror image of the side shown in FIG. 2.

FIG. 1

FIG. 2

FIG. 3

FIG. 4
